Patented Aug. 8, 1922.

Attorney

UNITED STATES PATENT OFFICE.

ELVIN LANDIS, OF MASSILLON, OHIO.

RAILROAD CROSSTIE

1,425,104.

Specification of Letters Patent. Patented Aug. 8, 1922.

Application filed April 13, 1922. Serial No. 552,248.

To all whom it may concern:

Be it known that I, ELVIN LANDIS, a citizen of the United States, residing at Massillon, in the county of Stark and State of 5 Ohio, have invented certain new and useful Improvements in Railroad Crossties, of which the following is a specification.

This invention relates to certain new and useful improvements in railroad cross ties 10 and it has for its objects among others to provide an improved tie that shall meet all the requirements and yet be simple in its structure and mode of securing the rail in place, providing for use of rails of different 15 widths of base and yet securely holding the same in position and providing for such adjustment as may be necessary.

I form the tie proper of sections, the end 20 sections being of metal, hollow, and the intermediate section being of wood forming an insulating medium to take care of all bonded or automatic track circuits; there being no wear on this intermediate section it will be found capable of lasting for years.

25 It is preferably creosoted or otherwise treated to aid in its preservation.

I aim further at improvements in the details of construction whereby the tie is better adapted to serve in the capacity for 30 which it is intended and insuring greater safety in use.

Other objects and advantages of the invention will hereinafter appear and the novel features thereof will be specifically defined by the appended claims.

The invention, in its preferred form, is clearly illustrated in the accompanying drawings, which, with the numerals of reference marked thereon form a part of this 40 specification, and in which—

Figure 1 is a side elevation showing my cross tie with the rails secured in place thereon, the rails being shown in section.

Figure 2 is a top plan of Figure 1.

45 Figure 3 is a vertical longitudinal section on the line 3—3 of Figure 2, looking in the direction of the arrows.

Figure 4 is a vertical cross section on the line 4—4 of Figure 3.

50 Figure 5 is a sectional detail showing a modified form of wedge key.

Like numerals of reference indicate like parts throughout the several views.

Referring to the drawings—

55 1, 1 designate the end sections of the tie; these are of metal, preferably steel, hollow,

closed at the outer ends and open at the inner or adjacent ends. They are formed of sufficient strength and of the required dimensions, and are united by the intermediate 60 wooden section 2, the ends of the latter being inserted in the adjacent open ends of the sections 1, and extending thereinto for a sufficient distance; the wooden section is creosoted or otherwise treated for an obvious 65 purpose and the ends of this section 2 are secured within the end sections by means of the cross bolts 3 which may be secured in place in any suitable manner, preferably by cotter pins or the like 4, so the bolts may be 70 easily removed when desired.

The bottoms of the sections 1 are provided with openings 5 for the drainage of water that may find its way into the said sections.

The sections 1, at a proper distance from 75 their outer ends, are provided with openings 6 in their tops as shown for the reception of securing wedges. Adjacent these openings the tops of the sections 1 are formed with the enlargements 7, into which the said openings 80 extend, these enlargements being for the purpose of strengthening the sections at these points and forming an enlarged bearing for the wedges.

85 8 are the securing wedges. As seen best in Figure 3 the wedge has a body portion formed with a vertically elongated slot and a head portion 10 one face of which is tapered as seen at 11. Each end section has two of these openings 6, the same being 90 staggered as seen in Figure 2 so as to provide a wedge bearing near each edge of the tie in order to prevent possibility of tendency of the rail to twist in use. The wedges 8 after being inserted in the slots or openings 6 in 95 the sections 1 are tightened by means of the cross wedges 12, seen best in Figure 4, each of these wedges having a body portion with a plurality of openings 13 at one end while the other end is provided with the head portion 14 having a tapered face 15 as seen best in Figure 4.

100 By enclosing the wooden member substantially entirely within the end sections, which latter are closed at the top, I provide 105 a substantial bearing of the end sections throughout their length and yet provide space for the wedges above described.

110 In practice, the vertical wedges are first placed in position with their heads bearing against the top of the rail base as shown, and then the horizontal wedges are passed

through the wall of the end section and through the slot 9 in the vertical wedges 8 and through coincident openings 16 in the opposite wall of the end section and then 5 drawn tight and secured by means of cotter pins 17 or the like passed through the appropriate openings 13 in the extended ends of the said wedges 12. By this means the rails are securely fastened to the ties and 10 the wedge portions of the securing wedges 12 draw the vertical wedges tightly down to place and their wedge portions serve to firmly and securely hold the rail base in place. The holes 13 in the wedges 12 provide for 15 greater or less wedge action on the vertical wedges and consequently of the latter on the rail base.

In order to provide increased bearing for 20 the vertical wedges I form the interior of the end sections upon one side of the openings 6 therein with a rib 18 as seen in Figure 4 where the vertical wedge is shown as having an extended bearing thereagainst.

In Figure 5 I have shown a modified form 25 of vertical wedge 19 having a body portion with vertical slot 20 for the passage of its securing wedge 21, the same as in the form above described, but the head portion is formed with a differently shaped wedge 30 part 22 to give an extended bearing on the rail base: this form, however, is not well adapted for use in connection with different widths of rail base, but very efficient for the width of rail base for which it is made.

35 Modifications in detail may be resorted to without departing from the spirit of the invention or sacrificing any of its advantages.

What is claimed as new is:—

1. A cross tie formed of hollow end metallic sections and an intermediate wood section 40 enclosed substantially entirely within said

end sections with its ends out of contact with the end walls of said end sections, the end sections having upper walls the inner ends of which bear on the ends of the wood section and being provided with openings in the upper walls for the reception of rail securing wedges. 45

2. A cross tie having an end section formed with an opening in its upper wall for 50 the reception of a rail-securing wedge and a rib upon the interior thereof adjacent such opening and adapted to bear against such wedge to form an increased bearing therefor. 55

3. A cross tie having a hollow end section with an upper wall with a vertical opening therethrough adjacent a side wall, and formed with a rib upon the interior between which and the side wall a wedge passed 60 through said opening is received.

4. A cross tie having an end section closed at the top and formed with an opening in its upper wall, a wedge engageable in said opening and having a tapered head for engagement with a rail base, and a horizontal wedge engageable in openings in the side walls of the said end section and having a tapered head engageable with the vertical wedge, said section being formed exteriorly 70 and interiorly with means forming increased bearings for said wedges. 65

5. A cross tie having an end section with an opening in its upper wall, a vertical wedge with a vertical slot, and a horizontal 75 wedge adjustable in the side wall of said section and in the slot of the vertical wedge, said section being formed with an interior member forming an increased bearing for the vertical wedge. 80

In testimony whereof I affix my signature,
ELVIN LANDIS.
